JAMES S. DONNELLAN, OF LOS ANGELES, CALIFORNIA, ASSIGNOR OF ONE-HALF TO
JAMES R. SHAW, OF LOS ANGELES, CALIFORNIA.

FALSE TEETH, PLATE, MOLD, AND METHOD OF MAKING.

Application filed October 1, 1927. Serial No. 223,318.

My invention is in the construction of false teeth, the plates for such teeth, the molds for making the plates and the method of making such molds.

5 An object of my invention is the construction of a special mold which may be used with a hardening material, such as plaster of Paris, to obtain a cast of a person's mouth, such as the gums, to form plates in which 10 false teeth are set. In addition, my invention comprises the manner of using the molds to obtain the impression of the mouth and gums, and in modeling the molds from this cast and obtaining further casts until a satisfactory cast is developed.

A further object of my invention is the construction of plates for false teeth, especially for the lower jaw, in which such plate interlocks in a dovetail manner with the formation of the lower structure of the gums of 20 the lower jaw.

In connection with my invention I utilize molds for the upper and lower teeth. For the upper teeth I form a mold which may be 25 made of wax with a wire re-enforcing therein having the teeth set in the mold; or, I may use a metal plate, such as aluminum, with wax molded on the plate and upper teeth set in the wax. This plate or the wax mold has a 30 bridge adapted to fit against the roof of the mouth. The mold for the lower teeth is preferably made of wax with suitable wire re-enforcing, and with the teeth secured in the wax, and the mold has a pair of depending 35 lugs adapted to fit inside of the lower gum structure. These lugs may be curved slightly outwardly to fit inside the gum structure, being as close a fit as may be estimated by the operator in building the wax mold.

40 The mold for the lower teeth is preferably fitted first. In this case soft plaster of Paris, or other suitable hardening composition, is placed in the lower part of the mold, and this is fitted in the mouth, the plaster of Paris 45 conforming to the shape of the inside of the lower gum structure. The mold for the upper teeth has a plaster of Paris composition placed therein and this is fitted in the person's mouth. The patient then bites, pressing the 50 upper and lower teeth together in the exact

manner desired in the finished teeth. This forms impressions in the plaster of Paris which is allowed to harden before removal from the mouth. The molds with the plaster of Paris then exhibit the configuration of 55 both the lower and upper gum structures and the parts of the mouth adjacent thereto.

Should it happen that the wax molds previously made are not sufficiently accurate, either being considerably too large or too small, another set of wax molds is made with the teeth fitted therein, this being a more close approximation to the shape of the patient's 60 gums, as illustrated by the plaster casts which have been taken. These new molds may be 65 for both the upper and lower teeth, or merely one or the other.

If new molds are necessary, these are fitted in the patient's mouth, using the plaster of Paris or equivalent composition to obtain the 70 impression of the upper and lower gums, through the patient placing the molds in the mouth and biting the teeth together. After an impression is obtained in a mold, which is sufficiently similar to the plates desired 75 for the finished teeth, these are used in making hard rubber or other plates in the manner known in the trade, by casting operations, having the teeth molded therein.

My invention in its several aspects will be 80 more readily understood from the following description and drawings, in which:

Figure 1 is a perspective view of a mold having the upper teeth incorporated therein to obtain a cast of the upper part of the 85 mouth.

Fig. 2 is a longitudinal section on the line 2-2 of Fig. 1, illustrating in addition a plaster of Paris impression therein.

Fig. 3 is a view similar to Fig. 2 of a modification showing the mold formed of wax with a re-enforcing.

Fig. 4 is a perspective view of the mold for the lower teeth with the teeth incorporated therein viewed from underneath.

Fig. 5 is a cross-section approximately on the line 5-5 of Fig. 4 in the direction of the arrows.

Fig. 6 is a longitudinal section through the two molds when placed together in the 100

position of a person making the plaster of Paris impression by biting the teeth together.

Fig. 7 is a cross-section of the lower finished false teeth, illustrating the manner of interlocking or dovetail underneath and inside of the gum structure.

Referring to the mold of Figs. 1, and 2, this is designated as the upper tooth mold 11 and has a bridging plate 12 which, as shown in Fig. 2, is formed of metal and has an upturned flange 13 around the two sides and the front. A wax form 14 is built onto the metal bridge, this having a more or less vertical part 15 simulating somewhat in shape the outside of the gums of the upper jaw, and having an internal section 16 pressing the back of the teeth 17 to the bridge plate 12.

In the construction shown in Fig. 3, the bridge plate 20 is formed of wax and has a wire re-enforcement 21 embedded therein. This has an up-turned flange 22 which simulates the outside part of the gums of the upper jaw; the upper teeth 23 are embedded in the lower part of the flange, and there is a back support of wax 24 which backs up the teeth and connects to the bridge plate 20.

The mold for the lower jaw is designated generally by the numeral 30. This may be considered as a U-shaped mold having a curved base 31 in which the teeth 32 are embedded. This base has a substantially flat under surface 33 at the front which flat surface continues substantially to the rear 34 at each side, the top of the teeth and the bottom 35 of the base converging towards the back or molar teeth. There is a slight downwardly depending rim 35 on each outside edge, beginning about half way back on the sides and continuing to the rear of the mold. There is also a downwardly extending flange 36 on each side of the inside of the mold, this having a concave curve outwardly and downwardly. These flanges are at their greatest depth at about the mid position of the sides, and are of considerable depth compared with the width of each side of the mold. It is preferable to make the mold for the lower teeth of wax with a re-enforcing wire 37 or the like.

In making the mold for the lower jaw the operator, having matched the teeth which are to form the upper and lower set, makes the mold to a shape which he estimates will fit comfortably in the patient's mouth. The flanges 36 may be turned outwardly at the lower edge to a considerable extent, but this is not necessary. After both the molds have been made, they may be fitted in the mouth either by the operator or by the patient, the procedure being as follows: It is preferable to insert the lower jaw mold in the mouth first, and in doing this the mold is inverted and a plaster of Paris composition 40 is placed in this mold, the composition fitting on the somewhat flat surface 30, as indicated at 41, and extending around the sides, as indi-

cated at 42, also extending towards the rear 34, there being a considerable layer on the outside of the flanges 36. This need not be molded to shape but should be sufficiently pressed so that when inserted in the mouth it will hold the shape.

The patient inserts the mold in the mouth by first fitting the flange on one side so as to curve underneath the solid part of the jaw forming the gums, and then this is properly centered in the desired position in the mouth.

The upper mold is then used and has a plaster of Paris composition designated generally by the numeral 43. This is placed to a considerable depth in the front part, as indicated in Fig. 2, fitting against the flange 13 or 22, in accordance with whether a metal bridge plate flange is used or an all wax mold. This composition extends rearwardly on the bridge, as indicated at 45, being of sufficient depth to form an impression. This mold is then inserted, fitting in the upper jaw with the bridge adjacent the roof of the mouth and pressing the gums well into the plaster of Paris on the bridge and against the flanges. The upper and lower teeth are brought to the desired position that they should occupy in use, then the patient bites, pressing the teeth firmly together, which action embeds the gums and the flesh covering the bony structure of the upper and lower jaws into the plaster of Paris composition and causes this to flow filling all the void spaces and conforming to the shape of the gums and such fleshy structure of the upper and lower jaws.

If, on inspection of the impressions taken in the molds, the operator is of the opinion that it is desirable to make a new set of molds, these are made, setting the teeth in the position indicated as being approximately correct as shown by the impression of the gums and forming complete new molds. Frequently the plaster cast can be removed and the operator can re-work the molds already constructed into an approximate shape. Should this be done the patient makes an impression in the manner above described, using plaster of Paris or similar composition.

When a satisfactory cast has been obtained showing the impression of the gums, this impression on the wax mold or the wax mold with the metal bridge is used to form a mold for a hard rubber or other similar composition plate, in which the false teeth are to be embedded, the wax being melted and allowed to flow out of the mold and the plaster of Paris core being removed. The false teeth with the plate thereon for the upper set do not depart radically from false teeth and plates as now constructed as a finished article, but the manner of procedure to arrive at the correct shape is different from the present art.

In the false teeth and plate for the lower

jaw, the characteristics are quite distinct from those now used, this construction being illustrated in Fig. 7 in which the plate is designated generally by the numeral 50, this having a substantial body structure 51 of U-shaped formation in which the teeth 52 are embedded, the outside portion 53 simulating the outer part of the gums which are visible. The plate has a lower surface 54 which is substantially parallel to the upper edges of the teeth except that this surface draws upwardly towards the top of the molar teeth in the same manner as the mold, as indicated in Fig. 4. There are opposite rims 55 which extend downwardly slightly on the opposite sides about midway back of the tooth structure.

The heavy flanges 56 have a decided outward projection 57 at the bottom, these being on each side at the place indicated by the flanges 36 in the mold of Figs. 4 and 5. This leaves concave pockets 58 on opposite sides of the flanges of the plate. The inner surface 59 of the flanges has a convex curve and is sufficiently cut away to accommodate the person's tongue.

In fitting the completed false teeth with their plate in the lower jaw, one side is pressed into position under the flesh of the bony structure forming the gum. The plate is pressed towards the rear and the other side is slipped into position and the plate with the teeth is pulled forwardly. This causes the lateral extensions 57 of the flanges 56 to fit partly underneath this bony structure, and such structure fits in the pockets 58 in a species of dovetail connection. The false teeth with the plate are, therefore, firmly locked into position, and when properly fitted they are held in such firm relation to the lower jaw that it is somewhat difficult for the wearer to remove the teeth. The upper jaw set of teeth fit in the usual manner, and if the manipulation of the molds has been correct, the teeth will fit in the manner indicated they should fit in taking the impressions and forming the last mold.

A characteristic feature of my invention is that the wax mold for the upper teeth and the lower teeth is of a very strong construction, the upper mold having in one case either a metal bridge or a wire re-enforcement, and the lower mold having a wire re-enforcement. Therefore, after the impression of the gums has been made in plaster of Paris and this has hardened, the person into whose mouth the molds are fitted may use the teeth to bite hard substances such as crusts of bread, masticating these to see if a proper fit for proper mastication of the food has been obtained. This is a decided advantage of my molds over those as constructed in accordance with the prior art.

An important feature of the mold for the lower teeth is the construction having the depending flanges 36 which extend downwardly

from substantially a horizontal surface and on the inside of the U-shaped structure at the rear portion thereof. When the lower surface of the mold and the outside surface of these flanges are covered with the plastic composition and the mold fitted in the mouth, the patient biting on the teeth, the plastic composition is shaped somewhat as shown in Fig. 5. This has the outward bulges at the bottom conforming to the flesh and bony structure of the lower part of the jaw. Therefore, in the finished false tooth mounting as shown in Fig. 7 the pockets 58 allow the fitting of the bone and fleshy structure of the lower part of the jaw therein. This causes the lower set of teeth to lock in the jaw and the harder a person bites the tighter they lock therein. This construction prevents rocking of the lower set of teeth.

Various changes may be made in the principles of my invention without departing from the spirit thereof, as set forth in the description, drawings and claims.

I claim:

1. The method of making dental impressions comprising inserting a lower tooth mold in the mouth with the mold resting on the lower gum structure, the mold having a plastic composition on depending flanges adjacent the back and on the under surface and biting on an upper set of teeth, the lower mold forming an impression by squeezing the plastic material partly underneath the bony structure of the lower gums from the inside towards the outside.

2. In the method of making a dental impression of the lower gums, placing a mold having downwardly extending flanges adjacent the back with a plastic material on the outside of the flanges in the mouth, resting on the lower gums and biting against such mold, thereby forcing the impression-receiving material outwardly and underneath the bony structure of the lower gums.

3. A set of false teeth for the lower jaw having a supporting structure with depending flanges adjacent the back extending downwardly on the inside, said flanges having outwardly projecting extensions fitting underneath the bony structure of the lower gums

from the inside.

4. A set of false teeth for the lower jaw comprising teeth embedded in the supporting material, the supporting material being substantially U-shaped in plan and having a substantially flat under surface to fit on top of the gums and a pair of downwardly extending flanges on the inside, said flanges adjacent the back having outwardly extending portions adapted to form lateral pockets, said lateral pockets accommodating the flesh and bony structure of the lower gums on the inside thereof.

5. A set of false teeth for the lower jaw, comprising a supporting structure with teeth

embedded therein, this being substantially U-shaped in plan and having a substantially flat under surface to fit on top of the gums, a pair of downwardly depending flanges at the back and on the inside of the U, said flanges having outwardly extending portions at the bottom adapted to form lateral pockets, said lateral

pockets accommodating the flesh and bony structure of the lower gums on the inside thereof.

In testimony whereof I have signed my name to this specification. ¹⁰

J. S. DONNELLAN.
